UNITED STATES PATENT OFFICE.

FRANK O. HULT, OF GALESBURG, ILLINOIS.

KEY AND KNOB HOLDER FOR DOORS.

1,260,774.

Specification of Letters Patent. Patented Mar. 26, 1918.

Application filed January 2, 1917. Serial No. 140,269.

To all whom it may concern:

Be it known that I, FRANK O. HULT, a citizen of the United States, residing at Galesburg, in the county of Knox and State of Illinois, have invented certain new and useful Improvements in Key and Knob Holders for Doors; and I hereby declare that the following is a full, clear, and exact description of the invention, which will enable others skilled in the art to which it appertains to make and use the same.

This invention relates to an attachment for the knob-spindle of a door for securing the same to prevent it being turned. It also relates to an attachment for the said knob-spindle including an extension for engaging and preventing the key of the door being turned.

One of the objects of the invention is to provide an attachment to be clamped to the knob-spindle and for engaging the key or some other part stationary so that the knob cannot be turned, the latch with which the knob is in control thereby constituting a lock for the door.

Another object is to provide an attachment to be secured on the knob-spindle, a part of which may engage in the eye of the key of the lock whereby both the latch and the key controlled locking-bolt will serve to doubly lock the door.

To the end that the invention may be fully understood I have provided the accompanying drawing in which one or two forms of a device involving the principle of my invention are included, although other changes may be made that will be within my inventive idea and brought out by the claims.

Figure 1 shows the edge of a door and the usual knob-spindle and key, showing my invention in connection therewith.

Fig. 2 is a face view of a portion of the door showing the knob-spindle in section and my invention applied thereto.

Fig. 3 is a view similar to Fig. 1, showing a different position of the invention.

Fig. 4 is an enlarged detail of a modified form of the device involving my invention; and,

Fig. 5 is a longitudinal section of a part of the device on line $\alpha-\alpha$, Fig. 4.

A represents the door; B a part of the door lock, and C the escutcheon-plate. D is

the knob-spindle, E the latch controlled thereby, F the key, and G the locking-bolt which it controls.

H is a U-shaped member or yoke whose extremities are each furnished with an aperture J in line with one another. K is a bar 60 slidable through said apertures and provided at one end with a hook K', or otherwise formed, whereby to engage the shaft of the key.

Said yoke H is adapted to engage over the 65 knob-spindle D and may be of such a size that any size of spindle may be accommodated. Its inner face is preferably serrated as indicated at L whereby it will frictionally engage said spindle. The bar K is likewise 70 serrated as at M, for a like purpose, the aperture being of sufficient extent to permit the bar to be moved against the spindle to firmly clamp it.

N is a set screw constructed so that it can 75 be readily grasped by the fingers so that when the bar is set up against the spindle it may be secured in place.

When the knob only is to be held the bar is adjusted so that the hook K' thereof or its 80 equivalent may engage the key. In this relation of the parts, the device being securely clamped upon the spindle, the knob cannot be turned and, therefore, the latch E constitutes a lock for the door.

In addition, to the above, the key may be held so that it cannot be turned from the outside by dropping the hook end of the bar through the eye of the key as shown in Fig. 3. Thus the knob and key may both be 90 secured and the door doubly locked.

In Figs. 4 and 5 I have shown a modification in which the one extremity of the yoke is split. In these figures said yoke is indicated by the reference letter O and the 95 knob-spindle by P. Q is an aperture in one of the extensions of the yoke. The other extension, Fig. 5, is slotted at R to receive the bar S corresponding to K, the latter being slotted at T whereby it may be shifted 100 to permit the yoke to be placed upon or removed from the knob-spindle, the slotted bar being prevented from becoming detached from the yoke by hanging on the bolt U.

In addition, the yoke is slotted as at V 105 to permit the bar S to move in the direction of the spindle P so that spindles of differ-

ent diameters may be easily clamped, the yoke and bar being serrated as already described in connection with the other figures.

The bolt U extends entirely through the yoke extremity and when tightened in a nut W or equivalent portion clamps the bar S firmly in place.

In the other figures in order to attach or detach the device, the bar is removed from the yoke, the set screw N merely extending far enough into the latter to frictionally engage the bar.

Preferably I provide the hook K' for the bar, which when the device is carried in the pocket, the hook may be used as a shoe-buttoner. The parts are all preferably made of hardened steel so that the serrations can be forced more or less deeply into the spindle and absolutely prevent that member being turned.

Having thus described my invention, I claim:

1. In a device for securing the knob spindle of a door, a U-shaped yoke having a serrated inner surface to engage and grip the spindle and having an opening in each extremity substantially in line with one another, a bar arranged to engage in both openings and having a serrated face to engage and grip the spindle, and means to secure the bar relatively to the yoke and the spindle, said bar having an extension adapted to engage a part fixed relatively to the door.

2. In a device for securing the knob spindle of a door, a U-shaped yoke having a serrated inner surface to engage and grip

the spindle and having an opening in each extremity substantially in line with one another, a bar arranged to slidably engage in both the openings in a longitudinal direction and adapted to have lateral movement in said openings, said bar having a serrated face to engage and grip the spindle at a point opposite the part thereof gripped by the yoke, a clamping device carried by an extremity of the yoke for clamping the bar, the latter having a hooked extremity to engage a part extending from the door.

3. In a device for securing the knob spindle of a door, a U-shaped yoke having a serrated inner surface to engage and grip the spindle and having an opening in each extremity substantially in line with one another, a bar arranged to slidably engage in both the openings in a longitudinal direction and adapted to have lateral movement in said openings, said bar having a serrated face to engage and grip the spindle at a point opposite the part thereof gripped by the yoke, a clamping device carried by an extremity of the yoke for clamping the bar, the latter having a longitudinal slot substantially equal in length to the width of the yoke, the bar being maintained in permanent connected relation with the yoke, said bar also having an extension adapted to engage a part carried by the door.

In testimony whereof I affix my signature, in presence of two witnesses.

FRANK O. HULT.
